DESIGN FOR PLAY SUIT

Max Gelber, Hackensack, N. J., assignor to American Novelty Wash Suit Company, a corporation of New Jersey

Application May 12, 1934, Serial No. 51,758

Term of patent 3½ years

To all whom it may concern:

Be it known that I, Max Gelber, a citizen of the United States, residing at Hackensack, in the county of Bergen and State of New Jersey, have invented a new, original, and ornamental Design for Play Suit, of which the following is a specification, reference being had to the accompanying drawing, forming part thereof.

Fig. 1 is a front view of the suit constituting my design and Fig. 2 is a rear elevational view thereof.

I claim:

The ornamental design for play suit, as shown.

MAX GELBER.
